UNITED STATES PATENT OFFICE.

JOHN L. MOHUN, OF NEW YORK, N. Y., ASSIGNOR TO CHICAGO RAILWAY EQUIPMENT COMPANY, OF CHICAGO, ILLINOIS, A CORPORATION OF ILLINOIS.

COMBINATION BRAKE-BEAM GUIDE AND SAFETY-GUARD.

1,357,336.

Specification of Letters Patent.

Patented Nov. 2, 1920.

Application filed July 11, 1919. Serial No. 310,146.

To all whom it may concern:

Be it known that I, JOHN L. MOHUN, a citizen of the United States, residing at the city of New York, in the State of New York, 5 have invented a certain new and useful Improvement in Combination Brake-Beam Guides and Safety-Guards, of which the following is a full, clear, and exact description, such as will enable others skilled in the art 10 to which it appertains to make and use the same, reference being had to the accompanying drawings, forming part of this specification, in which—

Figure 1 is a side elevational view of my 15 improved combination brake beam guide and safety guard.

Fig. 2 is a similar view of a modified form.

Fig. 3 is a similar view of a modified 20 form, and

Fig. 3^a is a similar view of another modified form.

This invention relates to a new and useful improvement in combination brake beam 25 guide and safety guard, the object being to apply a device of the character described to a car truck without employing any special means of attachment to the truck.

My improvement consists in a frame 30 which extends across a spring plank and is supported by the brake beams in such a way that it forms a guide for the beams when they are being applied to the wheels and also a support for the beams in the event of 35 failure of the brake hangers, brake levers or other brake beam supports.

In Fig. 1, I have shown one form of my 40 invention in which 1 indicates the spring plank and 2 the bolster of an ordinary truck, 3 are the wheels and 4 the axles of the truck. 5 indicates brake beams which are suspended by the usual hangers (not shown), said brake beams consisting of compression members 6 and tension members 7.

45 In Fig. 1, 8 indicates a casting extending across and over the spring plank 1 having nose extensions 8^a which rest upon the compression members of the brake beam, said casting having underhung extensions 8^b spaced apart from the nose portions 8^a so as to accommodate the compression members 6 of the brake beams. These extensions 8^b are 50 preferably I-shape in cross section so as to provide tracks on which castings 9 having

lips at their outer extremities which engage 55 the top flange of the I-shaped portion 8^b and constitute a support for a tension member of the brake beam. Retaining guides 1^a carried by spring plank 1 prevent the lateral movement of casting 8.

60 In Fig. 2, I have shown an underhung casting 10 which is provided with reentrant overhanging ends 10^a extending over the spring plank, which reentrant overhanging portions provide spaces for receiving the 65 compression members 6^a of the brake beam, and which compression members support the casting 10. 11 indicates springs carried by the casting 10, whose outer ends embrace the tension member 7^a of the brake beams so as 70 to retract them when released. Retaining guide 1^b carried by spring plank 1 prevents the lateral movement of casting 10.

In Fig. 3, I have shown a plate or built-up structure in which 12 indicates a member 75 extending across the spring plank 1, and whose outer end is bent to provide a track 12^a for a wear shoe 13 carried by the tension member 7^b of the brake beam, of which 6^b represents the compression member. There 80 is a bent plate 14 secured to the plate 12 so as to extend under the compression member 6^b and a rubbing plate 15 is arranged on the spring plank 1 to serve as a chafing surface.

In Fig. 3^a, I have reversed the plate arrangement in making the plate 12^b straight and extending the under plate 12^c secured thereto outwardly so as to provide a track 85 for a shoe 13^b on the tension member 7^c of the brake beam of which 6^c represents the 90 compression member.

In all forms of my invention, it will be noted that the compression members of the 95 brake beams on each side of the spring plank constitute the supports for a member which serves to guide the brake beam, through the tension rods, and hence the 100 brake beams are easily applied to the wheels and the top of the shoes prevented from “riding the wheel” at the time the brakes are released.

It will be readily understood that minor 105 changes in the size, form and construction of the various parts of my device may be made and substituted for those herein shown and described without departing from the spirit of my invention, the scope of which is set forth in the appended claim.

What I claim is:

A guide for brake beams consisting of a floating member disconnected from the truck but articulated therewith and limited both 5 as to its vertical and lateral movement, said member being supported by the brake beams and provided with means whereby in the

event that the truck hangers or other beam supports are disabled, said member will support the beams from the truck.

In testimony whereof I hereunto affix my signature this 27th day of May, 1919.

JOHN L. MOHUN.
